WEB TENSIONING FOR WEB SPLICING MACHINES

Charles L. Ricards, South Plainfield, N. J., assignor to Wood Newspaper Machinery Corporation, Plainfield, N. J., a corporation of Virginia

Original application September 1, 1937, Serial No. 162,002, now Patent No. 2,272,225, dated February 10, 1942. Divided and this application November 14, 1941, Serial No. 419,207

7 Claims. (Cl. 242—75)

This invention relates to a double arm magazine reel, for use in the printing industry, combined with a pasting device wherein separate tension devices serve the two roll positions but are controlled from a common source. Its purpose is, of course, to use two rolls of paper to feed a continuous web into the printing press by splicing a new roll of paper to each expiring roll when the old roll is used up. The splicing is accomplished while the press is running at its normal rate of speed for printing and involves a knife which will sever the web coming from the expiring roll of paper and the new web will then take the place of the expiring web and continue without interruption and feed the press.

The principal objects of this invention are to combine the feature of applying tension to the running roll controlled by the diameter of the roll while employing a magazine reel, one controlling means being used to govern both rolls as each becomes the running roll; to provide a double brake arrangement so that each brake takes care of one of the two rolls or spindles so that both sets can be and are controlled by a single regulating mechanism; to provide an improved arrangement for moving the spindles endwise when adjusting for side register; to provide means whereby the paper roll is constantly under control while being unwound and just after splicing; to provide an improved brake mechanism for each spindle or each roll of paper constituting the tension means; to provide a tension arrangement, the force of which will vary with the size of the paper roll and which will, as the paper roll decreases in size, gradually lessen down to a certain point, and then retain a tension on the roll when it is reduced in diameter and which can be released entirely when the pasting is to be made; to provide this braking arrangement in such a condition that, when the roll on which it is working is reduced to its smallest diameter, there will still be tension enough to apply the braking strain to control the butt as it is being unwound.

Other objects and advantages of the invention will appear hereinafter.

This application is a division of my application filed September 1, 1937, Serial No. 162,002, Patent No. 2,272,225 of February 10, 1942.

Reference is to be had to the accompanying drawings, in which

Fig. 1 is an end view of a reel and paster assembly illustrating a preferred embodiment of this invention;

Fig. 2 is a side view of the same;

Fig. 3 is an end view of a part of the same, looking in the direction of the arrow 3 in Fig. 2;

Fig. 4 is a side view of the paster mechanism;

Fig. 5 is a sectional view thereof on the line 5—5 of Fig. 4;

Fig. 6 is an end view of the same, looking in the other direction, the knife being in operative position, in Figs. 5 and 6;

Fig. 7 is a side view showing the general arrangement of the paper roll spindle, partly in section;

Fig. 8 is a side view of the paper reel central support shaft and connected parts;

Fig. 9 is an end view of the paper reel central support shaft, looking at the right end of Fig. 8, and

Fig. 10 is a wiring diagram.

This is a combination double arm magazine reel and pasting device. In other words, the reel moves around 180° to bring a new roll to the running position and, of course, the new roll is loaded when it is directly opposite to the running position. The rotation of the new roll to bring it up to web speed on its surface is supplied by a shaft from the press and controlled by the size of the roll.

The reel is supported by the two side frames 1 and 1a which rest on and are secured to a bed plate 2. The side frames are so designed that at 3 they form a box for revolvably supporting a reel support shaft 4.

Looking at Fig. 2 the reel support shaft 4 extends outside of a support box 5 on the side frame 1 and on its end is placed a large worm wheel 7 which is keyed to the shaft. This worm wheel engages with a worm 8 which is keyed to a shaft 9. The shaft 9 is supported in two lugs 10 and 11 which are integral parts of a worm wheel guard 12 which encloses worm gear 7 and worm 8. This guard is securely fastened to the side frame 1. The worm support shaft 9 extends outside of the hub 10 and on its extended end is fastened a hand wheel 13. From this it will be understood that when required to revolve the support shaft 4 it will only be necessary to revolve the hand wheel 13. A handle 14 is placed in the rim of the wheel 13 for conveniently revolving the hand wheel.

Immediately inside of the support boxes 5 and 6 on the support shaft 4 are placed brake drums 15 which are acted on by brake bands 17. These drums rotate freely on their support shaft 4. On the hub of each drum is fastened a gear 16. Each of these gears connects through intermediates 18 and 19 with a pinion 20 which is

fastened to the outside end of a paper roll spindle 21. It is to be noted that there are two of these spindles 21 operated from opposite ends. It will now be understood that, if necessary to put a braking action on a paper roll spindle, it is only necessary to tighten the proper brake band 17 on the drum 15. The actuating mechanism for the brake bands will be explained later.

The reason for the two brake arrangements on the support shaft is that each set takes care of one of the two paper roll spindles 21 and both sets can be and are controlled by a single regulating mechanism. The only difference between the two brake and spindle assemblies is that they are turned end for end.

On the end of the support shaft 4 opposite to the worm gear 7 is located a cam 50 (see Figs. 8 and 9). This cam operates a limit switch 48, the action of which will be explained further on. Each brake drum 15 carries an insulated commutator disc 51, which mounts a number of electrical contact rings 50, the action of which will be explained later.

Located in a fixed position on the support shaft 4 are double arm paper roll spiders 22. These are keyed to the shaft 4. At the two ends of the spiders are located the spindle sockets 23. These sockets, which are the bearings for the paper roll spindles 21, are supplied each with a hinged cap 24 which pivots on a hinge 25 and is held by a screw and thumb nut 26, for convenient removal of spindles.

The paper roll spindles 21 revolve in sockets 23. An arrangement for moving the spindles endwise as is necessary when adjusting for register is accomplished as follows:

On the end of each paper roll spindle 21 is fastened a grooved collar 27. The groove in this collar engages with a stud 28 which is fastened to the end of a lever 29. The end of the lever 29 pivots on a stud 30 which is fastened to the spider 22 by a poppet 31. In the middle of each lever 29 is located a screw threaded swivel poppet 31 which engages with a screw 32 which is operated by a hand wheel 33. The screw 32 is loosely fitted in a hole in a hub 35 on the spider 22, but is kept from end motion by a collar on the screw in one direction and the hand wheel 33 in the other. It will now be understood that by turning the hand wheel 33 in one direction or the other the screw 32 will move the lever 29 which in turn will move that spindle 21 endwise as required. The collar 27 is locked to the spindle 21 by a spring seated pawl 48 and sliding key 49 (see Fig. 7). To remove the collar it is only necessary to raise the pawl free of its engaging notch in the spindle and pull the collar off endwise.

On the spindle 21 are located the paper roll cones 36 and 37, the purpose of which is to locate, center and lock the paper rolls to the spindle. The cone 37 on one end of the spindle must also be easily removable to facilitate changing of paper rolls. The paper roll cone 37 is slidably fitted to the spindle 21. It is kept from rotating on the spindle by a sliding key 38 which is locked to the sleeve of the cone 37 by a rivet 39. A pin 40 is driven into the side of the cone sleeve and extends outside the surface. The purpose of this pin is to slip into a groove in the end of the paper roll core (not shown) and lock the paper roll from rotating on the spindle.

In back of the cone 37 is a sleeve 41. The sleeve's purpose is to lock the cone 37 on the spindle for endwise motion and to jam same

against end of the paper roll. The sleeve slides on the spindle but has a sliding key 42 which keeps it from revolving on the same. This key is fastened to the sleeve by a rivet 43. In a slot in the rear end of the sleeve is placed a spring seated pawl 44 which engages with a ratchet face that is cut in the side of the spindle 21. To lock the cone 37 in its proper position it will only be necessary to push the cone and sleeve to their proper position and the pawl will lock against backward motion. For fine adjustment of the cone and for jamming the cone against the end of the paper roll, a nut 45 is located on a threaded portion of the inside end of the sleeve 41. To jam the cone 37 against the paper roll it is only necessary to revolve the nut 45 so as to clamp it against paper cone, provided that sleeve 41 is locked on the spindle by the pawl 44. Pin holes 46 are provided in the nut 45 to facilitate turning the nut by a pin wrench or spanner.

At the other end of the paper roll 69 on the spindle 21 is located the paper roll cone 36. This cone itself is of the same design as the cone 37. This cone, however, is never removed and has only to be shifted endwise when the press is changed to run a different width of paper. For this reason, two lock nuts 47, which are threaded on the body of the spindle back up the paper roll cone against end motion. When it is necessary to change the location of the cone for a different size of paper, it is necessary only to move these nuts backward or ahead as required to locate the cone in its proper position.

On the brake side end of the spindle is located the brake engaging gear 20. This gear is fastened to the spindle in identically the same way as the collar 27 for easy removal when changing paper rolls.

In the operation of making a pasted splice between an expiring web and a new roll of paper it is necessary that the new roll should be revolved at a speed that will make the surface speed of the roll approximately the same as the speed of the paper being printed. This paper, of course, comes from the expiring butt. To accomplish this fact a belt 67, which is driven at paper speed, is arranged to contact with and, by friction, drive the surface of the new roll 69. This belt is driven by a pulley 66 which gets its drive from the press. The following will explain in detail this belt pulley drive and mechanism.

Looking at Fig. 1, 52 represents a part of the printing press. The driving shaft 53 is driven from the press at a speed relative to that of the printing cylinders. This shaft 53 is joined by a coupling 53^a to a shaft 53^b which has a running fit in a box 54, supported on a floor stand 55 and is geared to an input shaft 59 of a variable speed drive box 56 by gears 57 and 58. On the output shaft of the speed box 56 is keyed a bevel pinion 61 which engages with a bevel gear 62 which is keyed to a shaft 63. On the top end of the shaft 63 is keyed a mitre gear 64 which engages with a mitre gear 65 on the end of the shaft carrying the belt drive pulley 66. This constitutes the drive for the belt drive pulley 66 and belt 67. As it is necessary that the surface speed of the belt drive pulley 66 be the same as the surface speed of the printing cylinders, and as the printing cylinders vary in diameter to suit the required size of the printed matter, the variable speed device 56 is included in the gearing to compensate for the variation in the surface speeds of cylinders of different diameters.

The shaft 63 is supported at its lower end by

a bearing 71 which is an integral part of a bracket 72. The bracket 72 fastens to floor stand 55 which is fastened to the bed plate 2. At its upper end this shaft revolves in a bearing 68 which is bolted to an extension of the side frame 1.

The endless belt 67 wraps around the pulley 66 on a long arc. It runs around pulleys 70, 70 and 70 and is tightened by spring seated tightener 73. Belt pulleys 70, 70 and 70, as well as tightener 73 are all carried on a belt support arm 74. This arm is supported by and keyed to a support shaft 75, which swivels in hubs 76 which are integral parts of side frames 1 and 1^a. The belt support arm 74 may be raised up out of operating position or may be brought down against the new paper roll as required by moving an operating arm 77 which is keyed to the outside end of the shaft 75. A spring seated drop pin 78 in the lever 77, which is operated by a twisting handle 79 on the end of the lever, will engage any one of a number of holes or teeth 80^a in the edge of a segment 80, thereby locking the belt support arm in any operating position or in an inoperative position. The segment 80 is fastened to the outside of the side frame 1 by studs 82^a. On the end of the shaft 75 opposite to the lever 77 is located a lever 81 which is securely fastened to the shaft. The end of this lever is pivoted to a spring seated rod 82. This spring rod pivots on a stud 83 which is screwed into a hub on the lever 81. The other end of the spring rod is slideable in a poppet 84 which is screwed into the side frame 1. A spring 85 on the spring rod is compressed to a proper pressure between a poppet 84 and a collar 86 on the spring rod, to counteract the weight of the belt arm. After the splice has been made and the paper is running off the new roll, the reel spiders will be rotated in an anti-clockwise direction, as looking at Fig. 1, until a predetermined position has been reached. This position is reached when the center of the running roll is approximately in line with the position roll 87, as shown in Fig. 1. This is the proper running off position for the roll and will be kept until the butt is getting small enough to prepare for a new splice. At this same position of the upper end of the double spider the lower end of the spider is in the proper position for removing the old butt and loading a new roll.

As it is necessary that the paper roll be constantly under control while being unwound, the belt 67, just after splicing, is kept in contact with the roll until the running off position has been reached. At this point the new roll has contacted with and moved the roll 87 which controls the tension of the brake bands 17, and, since the brake now controls the running off of the web, the bolt 67 may be raised up out of contact with the paper roll.

The following will explain the brake mechanism (see especially Fig. 1). As the reel moves in an anticlockwise direction by turning the hand wheel 13, the newly spliced roll 69^a reaches the prefixed running position and the surface of the roll 69^a bears against the roll 87 and moves the same to the left. The roll 87 has a running fit lever 89. The lever 89 is fastened to a shaft 90 which swivels in holes in hubs 91 located in extensions of frames 1 and 1^a. The lever is so located on the shaft that it locates the roller 87 exactly in the middle of the paper roll which also is the center line between the side frames.

On the shaft 90, immediately inside of its supporting hubs 91, are securely fastened two levers 92, one on each side. On the free end of each of these levers is a stud 93 on which swivels one end of a turnbuckle 94. The other end of each turnbuckle connects with a pull spring 95 which is fastened to the end of the brake band 17. The other end of each brake band is fastened to the inside of the side frames 1 and 1^a by a stud 100.

It will now be readily understood that as the roll 87 is pushed to the left by the paper roll 69^a it turns the shaft 90 which in turn will move the levers 92 to the left. As the levers 92 move to the left they will put tension on the springs 95. This tension will, of course, vary with the size of the paper roll as the size of the roll governs the motion of the roll 87. The tension of the springs 95 will now act on the ends of the two brake bands 17 to give the proper braking strain. As the paper roll unwinds and gradually becomes smaller, the roll 87 will follow-up and thereby decrease the spring tension in proportion to the size of the roll. When it is necessary to release the brake bands completely as, for example, when making a paster when the new roll is driven by the belts 67, for selecting the running roll, or when changing paper rolls, the following device makes this possible.

Immediately inside of each frame 1 and 1^a is located a lever 96 which pivots on a stud 97 which fastens to the side frame. A bar 98 is loosely connected by a stud 99 to this lever. The other end of the bar 98 is loosely connected to the spring seated end of the brake band 17. By throwing the lever 96 downward until the lever locks past the center, it will have pulled the bars 98 with it which will unlock the brake band from the drum until again released.

After splicing and moving to the running position the paper roll may be unwound until it is time to prepare the butt for another pasting operation. At this time the tension regulating arm 89 will have moved so far to the right that it will strike against a brace 101 which connects the frames 1 and 1^a (see Fig. 1). This will stop the roller 87 from further motion. There is, however, still tension enough in the springs 95 to supply enough braking strain to control the butt as it is being unwound.

The reel will now be turned around by operating the hand wheel 13 in an anti-clockwise direction until the surface of the new roll 69^a comes within approximately one-half inch of the paster brush 102 which has been brought to a fixed position and locked there, as will be explained later.

The expiring butt will now be in its proper location for the splicing operation, as this position is automatically placed when the new roll 69^a in the opposite spindle position is placed in the right location to the brush 102.

At the extreme upper end of the side frames 1 and 1^a is located a shaft 103. This shaft supports the paster arms 104 which are keyed thereto. The shaft swivels in brackets 109, one at each end, which are securely fastened to the side frames 1 and 1^a.

The pasting mechanism is moved to operative and inoperative positions by a lever 105 which is keyed to the shaft 103 and located outside of the bracket 109 on the worm gear side of the reel. This lever engages a segment 106 which fastens to the side frame 1 and is so arranged that a spring seated lock pin 107 in the handle 108 of the lever may lock the lever in any required position. This, of course, is the means for locating

the paster arm 104 which in Fig. 1 is shown in pasting position.

The brush 102 is held in a brush holder 110. The brush holder is in the shape of a lever which pivots with a shaft 111 to which it is securely clamped. The shaft 111 swivels in brackets 112 which are secured to the paster arms 104. The brush 102 is urged by springs 113 towards the fresh roll but is kept from springing ahead by a pawl 114 which pivots on a stud 115 on the brush or paster arm 104. The pawl 114 is operated by a solenoid 116, mounted on a shelf 117 of paster arm 104, and is controlled by a push button, as will be described later. After the brush has been operated by pushing the button it is only required to move the brush arm 104 back to inoperative position and the brush will be automatically reset by a rod 118 of which upper end will strike against the fixed cam face 120 which is part of the paster arm support bracket 109.

Fastened to the ends of the brush arm support shaft 103 are located levers 121 and 122. The purpose of these levers is to counterbalance the weight of the brush arm arrangement by the pressure of springs 123 on spring rods 124.

Placed at the lower end of the brush arms 104 is located the knife 125 which is shown in Fig. 5 in operative position. It is guarded by a guard 126 which is fastened to a toe 127 on the brush arm 104. The knife is held in a holder 128 secured to a shaft 129 which is oscillatably supported in brackets 132 on the paster arms 104. On this shaft are located the two torsion springs 133 of which one end of each is fastened to a collar 131 and the other end to a support bracket 132. These springs urge the knife towards operating position but are kept from moving by a pawl 133 which engages a lever 134. This lever is pivoted at 135 and is electrically operated by a solenoid 136 which is fastened to a toe 137 on the paster arm 104. After the knife has been in operation it will be automatically reset when the brush arm 104 is brought to inoperative position. A crank arm 138 is placed on the end of the knife support shaft 129. This crank is pivotally connected to a rod 139 which slides through a poppet 141 mounted on a projection 140 of the bracket 109. It will be understood readily that when the brush arm is moved from one position to another there will develop a crank action between the brush arm and the fixed center of the poppet 141. This motion will be transferred by the rod 139 to the lever 138, thereby resetting the knife in inoperative position.

A tube 142 acts as a brace between the two arms 104. It also acts as a bar for the paper to slide on when the paper is running from the butt in pasting position.

The electrical equipment and the wiring diagram operate as follows:

Referring particularly to Fig. 10, lines L-1 and L-2, represent any sources of electrical power. The usual switch 143 and fuses 144 are provided. A line 145 runs to one side of a push button 146 which may be conveniently located on the frame of the machine. The other side of the push button 146 is connected to a line 147 which runs to contacts in said selector switch 148 which is shown in Fig. 9 as being operated by the cam 50. The low part of the cam connects one set of contacts carried therein while the high part of the cam connects the other. In this manner a selection is made of the particular spindle which carries the fresh web roll. A line 148 runs to a brush 149a which is shown

particularly in Figs. 10 and 8. This, when the switch 143 is closed and push button 146 is closed, will feed one side of the line to a center commutator ring 150. An insulated segment 151 is connected with the center ring 150 and when it passes a brush 152 it connects a line 153 with one side of the brush solenoid 116. The other side of the solenoid 116 is connected by a line 154 to the other side of the power. This establishes a circuit which energizes the brush solenoid 116, thereby causing the brush to press the running web against the fresh web roll as previously described.

The energizing of the brush solenoid 116 closes contacts 147a and 153a, thereby establishing a hold-in circuit for the brush solenoid. When the brush 102 moves forward to make the splice, the cam 155 on the shaft 111, as best shown in Figs. 4 and 6, operates a roller 156a on a switch 156, the latter being carried by the bracket on the brush arm and thereby permits contacts to be closed in this switch. This closing of contacts in the switch 156 connects line 154, which is one side of the power line, to a knife solenoid 136, the other side of which is connected by the line 157 to a brush 158 which cooperates with a contact segment 159 which is connected with the center ring 150 and then through the brush 149a, line 149, switch 148, line 147, push button 146 and line 145 to the other side of the line. This energizes the knife solenoid and permits the knife 125 to sever the web in a manner previously described. It also closes contacts 147b and 157b and thereby establishes a hold-in circuit for the knife solenoid. When the push button 146 is opened by the operator releasing the power the two solenoids 116 and 136 are disconnected and these solenoids are deenergized.

It is evident that, when the switch 148 operates to disconnect the lower contacts and connect the upper contacts, the commutator rings 51 serving the other spindle of the reel, are connected, thus the fresh roll may be first on one spindle and then the other, it being automatically selected to operate the brush and knife with respect to its angular position. It is evident that the commutator rings 51 always bear a definite relation to gears 16, 18 and 19. By placing a suitable marker on the gear 19 the fresh paste on the new roll 69a may be applied with reference to that marker and thereby insure proper operation of the brush and knife to make a successful splice.

The splicing operation will now be explained. As formerly explained, when the one paper roll is in its running off position, the opposite paper roll sockets are in the proper position for loading the reel. The expired butt will now be removed and a new roll be put in its place. In approximate line with a mark on the gear 19 the outside sheet will now be cut in the shape of saw teeth forming preferably two corners. Each of these corners will now be pasted to the surface of the paper roll by a paster tab. This tab is a piece of paper that has been weakened in the middle by perforations and is well known in the art. The one end of the tab will be pasted to the corner of the outside sheet and the other end pasted to the paper roll so as to smoothly and closely hold the outside sheet to the roll. Near the edge of the saw tooth shaped end of the sheet will now be spread a border of special paste. The paste will be continuous from end to end of the paper roll except for a portion in the center of

the roll which must be kept free of paste to make a clean path for the belt 67 and roll 87.

The expiring butt will now be watched. When it is considered small enough to prepare for splicing, the hand wheel 13 will be revolved causing the new roll to move in an anti-clockwise direction until a predetermined mark on the frame is reached. This is the proper place for splicing if the splicing position is reached. At this time the arm 104 will be moved to the right as far as it will go and locked, causing the brush arm 104 to be held in its proper position for splicing. Fig. 1 shows the brush arm in this position. The space between the brush and the roll will now be approximately one-half inch. The belt arm 74 has all this time been kept in its upper position with the belt 67 out of contact with the roll. It will now be lowered by moving the operating lever 77 to the left, bringing the belt 67 into contact with the surface of the roll. Since the belt is driven from the press at paper speed, it will now start the roll spinning at a surface speed equal to the printing speed.

When the paster is to be made it is then necessary only to make an electric contact by pushing the push button 146. This will operate the solenoid 116 which will make the brush force the paper from the butt against the surface of the new roll. The paste on the end of the outside sheet of the new roll will stick to the paper coming from the butt. The paste is strong enough to tear the two paster tabs and the paper from the new roll will run along with the paper from the butt. Immediately after the paster has been made the saw toothed knife will drop in the path of the paper coming from the butt and sever it. The new roll will now be moved to the regular running position by turning the hand wheel 13. The lever 77 will be moved to the right as far as it will go and locked, raising the belt 67 out of contact with the roll.

Having thus described my invention and the advantages thereof, I do not wish to be limited to the details herein disclosed, otherwise than as set forth in the claims, but what I claim is:

1. The combination with a double arm reel for supporting two web rolls, of two means for applying tension each to one web roll separately, a single controlling means for governing each tension means in succession as it goes into action on the running roll, means for causing the tension to vary with the diameter of the roll, and means to stop the lessening of the tension before the roll is exhausted.

2. In a magazine reel, the combination of two spindles for the fresh web roll and the running roll respectively, means for applying tension to the fresh web roll controlled at first by the diameter of that roll, means for applying tension to the running roll, and one controlling means for governing the application of tension to both rolls as each becomes the running roll.

3. In a web supporting reel, the combination of a central shaft, double arm paper roll spiders at opposite ends of said shaft, parallel spindles for the paper rolls at opposite ends of said spiders, each spindle being supported by bearings in both spiders, means on each spider for adjusting one spindle only longitudinally, braking means for each spindle on one end thereof, and means partly supported by each spider for applying said braking means to the end of each spindle.

4. In a web supporting reel, the combination of a central shaft, double arm paper roll spiders at opposite ends of said shaft, parallel spindles for the paper rolls at opposite ends of said spiders, each spindle being supported by bearings in both spiders, means on each spider for adjusting one spindle only longitudinally, braking means for each spindle on one end thereof, and means partly supported by each spider for applying said braking means to the end of each spindle, the two adjusting means being in opposite spiders and at opposite sides of the reel.

5. The combination with a magazine reel for supporting a running web roll and a fresh web roll, of a central shaft, a shaft for each roll, the latter two shafts each being connected with and supported by the opposite sides of the reel, two brakes, one on each side of the reel, each brake being arranged to control one of said shafts independently of each other and located on opposite sides of the reel, each brake involving a flexible brake band, two springs for applying force to the separate brake bands, a shaft, two levers on said shaft, each connected to one of said springs, another lever fixed to said last named shaft, and means on said lever for controlling the levers and springs in accordance with the size of the running roll during the first stage of its unwinding.

6. The combination with a magazine reel for supporting a running web roll and a fresh web roll, of two brakes, one on each side of the reel, said brakes being located on opposite sides of the reel, each brake involving a flexible brake band, two springs for applying force to the separate brake bands, a shaft, two levers on said shaft, each connected to one of said springs, another lever fixed to said shaft, and means on said levers for controlling the levers and springs.

7. In a web feeding device, the combination of a central shaft carrying two spiders, means for rotating the central shaft, a brake drum loosely mounted on the central shaft near each spider, two paper roll spindles, the ends of which are rotatably mounted in the arms of the spiders, means connecting one spindle to one of the brake drums and the other spindle to the other brake drum, and means for retarding the rotation of the brake drum to regulate tension in the web.
